SAVINGS BANK OR SIMILAR ARTICLE

Constance Constable de Bisschop, Honolulu, Territory of Hawaii, assignor to Bank of Hawaii, Honolulu, Territory of Hawaii, a corporation of the Territory of Hawaii

Application February 2, 1954, Serial No. 28,783

Term of patent 14 years

(Cl. D34—11)

To all whom it may concern:

Be it known that I, Constance Constable de Bisschop, a citizen of the United States and a resident of Honolulu, in the Territory of Hawaii, have invented a new, original, and ornamental Design for a Savings Bank or Similar Article, of which the following is a specification, reference being had to the accompanying drawing, forming a part thereof.

On the drawings:

I claim:

The ornamental design for a savings bank or similar article, substantially as shown.
